UNITED STATES PATENT OFFICE.

FREDRICK BENNETT, OF NEW YORK, N. Y.

AUTOMATIC LEG FOR FOLDING BEDS.

SPECIFICATION forming part of Letters Patent No. 427,293, dated May 6, 1890.

Application filed November 13, 1889. Serial No. 830,232. (No model.)

To all whom it may concern:

Be it known that I, FREDRICK BENNETT, of the city, county, and State of New York, have invented a new and Improved Automatic Leg 5 for Folding Beds, of which the following is a full, clear, and exact description.

The object of my invention is to provide a leg for folding beds which shall be so constructed and arranged that upon the lowering 10 of the bed it will, by gravity, fall out to position for supporting the bed and be securely locked, and upon elevating or closing the bed will fall back to full concealment.

Reference is to be had to the accompanying 15 drawings, forming a part of this specification, in which similar letters of reference indicate corresponding parts in all the figures.

Figure 1 is a front elevation of the upper 20 part of a folding bed having my invention applied thereto. Fig. 2 is a sectional elevation of the same on line xx of Fig. 1. Fig. 3 is a sectional view showing the leg in position to support the bed. Fig. 4 is a detailed sectional 25 plan view. Fig. 5 is a perspective view of the leg-box, and Fig. 6 is an enlarged perspective view of the leg removed.

A represents the upright portion of a folding bed, and B represents the bed-bottom. These may be of the usual or of any approved 30 construction, save that the bed-bottom may have side pieces B' and apertures d^3 d^3 for the legs D. The legs D act by gravity. They are made in angular form, and when the bed is closed rest upon inclined ledges c, which cause 35 the legs to recede upon lifting the bottom to a vertical or closed position. When the bottom is lowered to horizontal position, the legs drop through the apertures d^3 , as shown in Fig. 3, and at the same time a locking button 40 or pawl E drops to vertical position and engages with the shoulder d of the leg and holds it firmly in position to support the bed-bottom. The said shoulder d is by preference curved to correspond with the arc described 45 by the lower end of the locking-pawl E, which is pivoted at e, and upon the lifting of the bottom swings unassisted to the position shown in Fig. 2 out of the way of the automatic inward movement of the leg, due to the 50 incline c. The outward movement of each

leg is limited by the shoulder d' striking upon the ledge d^2 . The leg and pawl are by preference inclosed in a metal box F, one wall of which may be formed with the incline c; or the incline may be a small block of wood, as 55 shown in the drawings.

To facilitate the ready action of the leg, I provide it with rollers f, one or more, which rest upon the said incline c, as shown.

When necessary or convenient to fasten 60 the bed-bottom slat or cross-piece to which the bed spring or springs are attached to the boxes F, each will be provided with a suitable fastening, consisting in this instance of a supporting-lug m, an outwardly-projecting 65 plate m', and a set-screw m², fitted therein, as shown clearly in Fig. 5; but these parts may be omitted, if desired.

Having thus described my invention, I claim as new and desire to secure by Letters 70 Patent—

1. In a folding or wardrobe bed or other folding structure, the combination therewith of a bent leg, a box for retaining the same, an aperture in the bottom of the structure for 75 the leg, a pawl pivoted to the top of the box opposite the said opening, and one inclined surface of the box facing the pawl and said opening, and which supports the leg and forms an incline for causing the backward 80 movement of the leg by gravity when the structure is tipped to vertical position, substantially as described.

2. In a folding or wardrobe bed or other folding structure, the leg D, having shoulder 85 d', in combination with the pawl E, pivoted above the leg, and the inclined surface c, on which the leg rests when the leg is in horizontal position, substantially as described.

3. In a folding bed, the bed-bottom formed 90 with apertures d, and provided with the boxes F, combined with the bent legs D and pawls E, placed in said boxes, and the inclined surface c, also in said boxes, and which support the legs when in horizontal position, substan- 95 tially as described.

FREDRICK BENNETT.
